SUBMERSIBLE TRAILER LIGHT

Paul A. La Violette, 140 Hartley St.,
North Haven, Conn. 06473

Filed Sept. 28, 1972, Ser. No. 292,865

Term of patent 7 years

Int. Cl. D26—06

U.S. Cl. D48—32 R

FIG. 1

FIG. 2

FIG. 3

FIG. 4

FIG. 5

FIG. 1 is a front elevational view of the submersible light showing my new design, the cross-hatching of the peripheral portion of the transparent front lens representing a prismatic formation molded into the undersurface of that portion;

FIG. 2 is a side elevational view looking from the right in FIG. 1 and showing a translucent side lens with prismatic formation on its undersurface;

FIG. 3 is a rear elevational view;

FIG. 4 is a side elevational view looking from the left in FIG. 1; and

FIG. 5 is a top plan view.

The cross-hatching representing prismatic formation is partially shown in FIG. 2 for convenience of illustration, it being understood that the formation is uniformly continuous over the outlined area.

I claim:

The ornamental design for a submersible trailer light, substantially as shown and described.
